UNITED STATES PATENT OFFICE.

FREDERICK BENNETT, OF RAVENSWOOD, NEW YORK, ASSIGNOR TO WALKER & BENNETT MANUFACTURING COMPANY, OF NEW YORK, N. Y., A CORPORATION OF NEW YORK.

CAR-SEAT.

1,267,500.

Specification of Letters Patent. Patented May 28, 1918.

Application filed October 18, 1913, Serial No. 795,981. Renewed October 26, 1917. Serial No. 198,742.

To all whom it may concern:

Be it known that I, FREDERICK BENNETT, a citizen of the United States, residing at Ravenswood, in the county of Queens and 5 State of New York, have invented certain new and useful Improvements in Car-Seats, of which the following is a specification.

This invention relates to improvements in car seats, of the "walkover" type, or that 10 type in which the back of the seat is shifted from one side of the seat to the other.

The primary object of the invention is to provide a seat which is capable of being swung upon its pedestal to an upright or 15 substantially upright position, to make a clearance between the pedestal and the wall of the car for cleaning purposes, and for gaining ready access to the heating pipes and other apparatus usually located adjacent to the wall of the car.

Incidentally, the invention has for an object, to provide a construction whereby the seat may be bodily removed from the pedestal without disturbing the pedestal and to 20

provide a lock between the free end of the seat and a suitable wall-bracket, or a bracket supported adjacent to the wall of the car, and a still further object is to provide means whereby the back may be readily shifted 25 from one side to the other together with the shiftable connected parts.

A further object of the invention is to so construct the parts of the seat back which operate the rockers to shift the same from 30 one side of the seat to the other, that it will permit the positioning of the seat sufficiently above the floor of the car to clear the heating pipes, etc., usually located along the floor of 35 the car, adjacent to the wall.

Referring to the drawings—

Figure 1 is a front view of the seat, in tilted position, the seat and back cushions being indicated in dotted lines;

Fig. 2 is a transverse central section, looking toward the wall of the car, pedestal and cushions being indicated in dotted lines;

Fig. 3 is a top plan view of the seat; the cushion being removed;

Fig. 4 is a detail vertical section of the 50 aisle end plate and adjacent parts, taken about on line $a-a$ of Fig. 3;

Fig. 5 is a detail perspective view of the locking means carried by the wall end-plate;

Fig. 6 is a perspective view of one of the 55 back-standards;

Fig. 7 is a detail view of the upper portion of a pedestal arm, showing in juxtaposition thereto, the T-connection by which the pedestal is connected with the tie-rods of the seat.

Referring to the drawings, the numeral 1 designates the pedestal which is formed of a lower part 2 adapted to be attached to the floor, and an upper part 3 formed with a horizontal portion 4 and upwardly extending arms 5, which are separably connected with the tie-rods 5' which connect the end-plates. The horizontal portion of the upper part of the pedestal is hinged to the lower part by means of a clip 6 provided centrally 60 with a slot 7 for the passage of a stud 8 integral with the horizontal portion 4 of the upper pedestal part. This stud and slot arrangement is for the purpose of limiting the swinging movement of the seat, for obviously when this stud engages the lower end of the slot the seat can be rocked no farther. The stud has other functions which will be later described.

The numeral 9 designates the outer end-plate and the numeral 10 designates the inner or wall end-plate. These end-plates are preferably formed of pressed steel and are provided with inwardly extending flanges 11, so as to form a housing for the 70 track, lock mechanism, etc.

The numeral 12 designates a track formed with upper rails 13, and lower rails 14 and it will be understood that these tracks are 75 duplicated in each end-plate. The lower rail 14 of the track is shorter than the upper rail, thus forming recesses 15 to receive one or the other of antifriction rollers 16 carried on short studs on the broadened ends of the back-standards 17, between which back-standards, the back cushion is secured.

Connecting the lower ends of the back-standards is a rod 18 having a dropped central portion 19 which extends through an elongated slot 20 in the side bars of the 80 foot-rest 21, which side-bars are connected by a cross-bar 22. The side bars of the foot-rest are pivoted upon a central rod 23 which extends between the end-plates and is rigidly secured to a cross-bar 24 on each end-plate, and these side-bars are extended above their pivots and are provided with laterally 85 extending studs 25 which work in yokes 26 mounted centrally upon rockers 27 which support the seat-cushion. These rockers rest 100

105

110

upon the tie-rods 5' and are provided with inclined underneath surfaces 28 so that when the rockers are shifted, the proper inclination relative to the back of the seat 5 will be given to the cushion.

So that the seat may be readily lifted from the pedestal, I employ as connecting means between the arms of the pedestal and the tie-rods 5', T-connections 27' with the 10 tie-rods extending through the horizontal portions of the connections, and the upper ends of the pedestal arms extending into the vertical portions of the connections, as shown in the various figures. Connected to 15 the bottom of the aisle end-plate, is a laterally extending arm 29 which is provided at its inner end with an aperture 30 for the passage of the stud 8. The stud 8 is threaded and provided with nut 31 which is 20 screwed down on the top of the plate 29, thus securing the end-plate to the horizontal portion of the upper pedestal member. By this arrangement, when the seat is rocked upward, the tie-rods are prevented from 25 slipping through the T-connections. When it is desired to remove the seat bodily from the pedestal, the nut is removed, when obviously, the seat may be lifted from the pedestal.

30 The numeral 32 designates the wall-bracket which may be secured, in any suitable way, to the wall of the car, or in some circumstances, it may be supported by a pedestal adjacent to the wall of the car. 35 This bracket is formed with laterally extending side flanges 33 and a bottom flange 34 which forms a seat for the inner end plate of the car seat. The numeral 35 designates a sliding lock which is provided at 40 opposite ends with heads 36 and has integral therewith a head 37 provided with two shoulders 38. This lock, as shown in Figs. 2 and 5 rests upon the bottom flange 39 of the inner or wall end-plate 10, and slides 45 thereon. The bottom flange of the end-plate, as well as the bottom flange 34 of the wall-bracket, is provided with an elongated slot 40 through which the narrowed portion of the head 38 extends, so that the 50 head is brought into position below the flange 34, to engage one or the other edge of the slot. The lock is guided and its lateral motion is limited by a pin 41, passing through a slot 42 in the sliding lock. 55 On the wall side of the seat, the rod 18 is extended through a broadened portion of the back standard and presents a short stud 43, adapted to engage the heads 36 of the sliding lock when the seat-back is shifted 60 from one side to the other. When the seat-back has been thrown over sufficiently far to cause the lug 43 to engage one of the heads 36, but short of its entire movement, the sliding lock will be forced to a central 65 position wherein the head 37 may be with-

drawn through the elongated slot of the flanges 34 and 39 of the wall-bracket, and wall end-plate. In this position, obviously, the seat may be rocked out of the bracket, but when the seat-back occupies its final 70 position in either direction when one of its lower inclined edges rests upon the flange 39, the stud 43 will have forced the sliding lock to a position where one of the shoulders 38 will be in engagement with the under 75 face of the flange 34, hence locking the seat to the wall-bracket.

In operation, when it is desired to shift the back from the position shown in full lines, Fig. 2 to a position precisely opposite, 80 force is applied to the back which will lift the outer roller out of its recess 15, when the back will travel across the seat, guided by the tracks. This movement will cause the rod 18 to operate upon the foot-rest, rocking 85 it upon its pivot 23 and through the stud and yoke connections between the rockers, said rockers will be shifted, carrying the cushion with them. When it is desired to unlock the seat from the wall-bracket, the 90 back is forced over until the lug 43 engages the head 36 of the sliding lock and when the lock has been forced to central position, the seat is rocked on its pivot, using the 95 back as a means for throwing it over.

Having thus fully described my said invention, what I claim is:

1. A car seat, having in combination a seat hinged at one end to a fixed support and detachably supported at the other end, back standards, means for locking the detachably supported end of the seat to its support, and means carried by the back standards for unlocking the detachable end of the seat, so as to permit it to be raised.

2. A car seat, having in combination flanged end plates; a seat detachably supported at one end by a flanged support and hinged to a pedestal at the other end, a seat back, means for guiding the seat back and its accessories in their travel; back standards; a slideable lock carried by the detachable end of the seat, for locking the detachable end of the seat to the flanged support, said lock being provided with a locking head 105 adapted to pass through a slot in the flanged support and engage either edge of the slot, so as to lock the detachable end of the seat to the support, and means carried by the seat back to shift the lock from its engagement with the flange, so as to permit the detachable end of the seat to be lifted.

3. A car seat, having in combination a seat hinged at one end to a pedestal and detachably supported at the other end by a 115 flanged end plate; back standards, means for shifting said back standards from one side of the seat to the other, a slideable lock adapted to lock the detachable end of the seat to the flanged end plate; end heads carried by 120

130

the slidable lock, and a rod carried by the back standards for shifting the slidable lock, so as to permit the detachable end of the seat to be raised and swung over upon the pedestal.

5 4. A car seat, having in combination a seat hinged at one end to a pedestal and detachably supported at the other end, means for locking the detachable end of the seat 10 to its support; means for disconnecting the hinged end of the seat from its pedestal; back standards provided with means for shifting the same from one side of the seat to the other; and means carried by the back 15 standards for unlocking the detachable end of the seat, so as to permit the seat to be lifted from its respective end supports.

5 5. A car seat, having in combination a seat detachably supported at one end and 20 hingedly supported at the other end; a track at each end; back standards; a slidable lock for temporarily locking the detachable

end of the seat to its support; and a connecting rod carried by said back standards, adapted to unlock the slidable lock, so as to 25 permit said detachable end of the seat to be lifted.

6. In a car seat, locking mechanism comprising a flange suitably supported, said flange having a slot or recess and a correlative member supported by a car seat, said member having a double flanged head projecting therefrom, said head being adapted to pass through said slot or recess of the flanged support and also being adapted to 30 slide so as to effect a locking relation between the car seat and supporting flange.

In testimony whereof I affix my signature in presence of two witnesses.

FREDERICK BENNETT.
